UNITED STATES PATENT OFFICE.

NAOTARO YAMASAKI AND BUNZO WATANABE, OF FRONTIER, WYOMING.

MOUSETRAP.

Application filed April 24, 1924. Serial No. 708,765.

To all whom it may concern:

Be it known that we, NAOTARO YAMASAKI and BUNZO WATANABE, citizens of Japan, residing at Frontier, in the county of Lincoln and State of Wyoming, have invented certain new and useful Improvements in Mousetraps; and we do declare the following to be a full, clear, and exact description of the invention, such as will enable others skilled in the art to which it appertains to make and use the same.

Our invention relates to improvements in traps for mice, rats and the like, and has reference more particularly to devices of the trap-door type, in which the prey is dropped into a container which preferably contains water to drown them.

The object of the invention is to provide a simple and inexpensive device of the class set forth which embodies a cover plate for a receptacle, said plate having an opening, a second plate fitting loosely within said opening and centrally pivoted on one axis, said second plate also having an opening, and a third plate pivotally mounted within the last mentioned opening, on an axis at an angle to the first named pivotal axis. It is thus insured that a mouse or the like, treading in any manner upon the device, will be discharged thereby into the receptacle below.

With the foregoing in view, the invention resides in the novel subject matter herein-after described and claimed, the description being supplemented by the accompanying drawing.

Figure 1 is a perspective view.

Figure 2 is a vertical section.

In the preferred form of our invention, selected for illustration in the present application, we make use of three suitable plates 1, 2 and 3, which may be formed of tin, aluminum, or any other light, inexpensive material.

The plate 1 is shown of circular form, though it could be of other outline, and said plate is adapted to rest upon a suitable receptacle 4 which may well contain water or other liquid 5, to drown the prey. The plate 1 is formed with a relatively large opening 6 which is preferably, although not

necessarily, of circular outline, and loosely received in this opening, is the plate 2, said plate being balanced and pivotally supported upon a pair of pivot pins 7 which are disposed in axial alinement, said pins being connected at one end to the plate 1 and at their other ends to the plate 2.

The plate 2 is formed with a comparatively small opening 8, within which the plate 3 is loosely positioned, said plate 3 being balanced and pivotally supported by pins or the like 9 which are preferably at right angles to the pins 7, the outer ends of said pins 9 being connected with the plate 2, while their inner ends are connected with the plate 3. In connecting these pins and plates, and the pins 7 with the plates 1 and 2, we may well stamp pin-receiving knuckles 10 from the plates, as shown.

When the device is in place on the receptacle, inclined boards or the like 12 may rest against the latter to serve as runways, upon which the mice or rats may walk, in attempting to reach the bait in the holder 11. If they tread upon the plate 2, out of line with the pivot pins 7, this plate will immediately tilt and discharge them into the receptacle 4, and if they should attempt to jump and free themselves when falling, and so should gain a foot-hold upon the plate 3, the latter will tilt, so that they cannot by any chance reach safety. Furthermore, if a mouse or the like should walk across the plate 2, in line with the pivots 7, the moment he steps upon the plate 3, he would be caused to fall into the receptacle 4.

As excellent results may be obtained from the details disclosed, they may well be followed, but within the scope of the invention as claimed, changes may be made.

We claim:

A trapping device adapted to form a cover for a receptacle, said device comprising a flat supporting plate adapted to be supported by the receptacle, said plate having an opening, a flat trap plate disposed within said opening and pivoted between its ends to said supporting plate to swing freely in either direction, said trap plate having an opening, and a second flat trap plate disposed within the second named opening

and pivoted between its ends to said first trap plate to freely swing in either direction, the pivot of said second trap plate being disposed at right angles to the pivot of said first trap plate, whereby a mouse or the like attempting to walk across the device in any direction toward the center of the second trap plate will be dropped through one or the other of said openings. In testimony whereof we have hereunto affixed our signatures. 10

NAOTARO YAMASAKI.
BUNZO WATANABE.
